UNITED STATES PATENT OFFICE.

JAMES F. CROOKER, OF BUFFALO, NEW YORK.

DESIGN FOR A BICYCLE-STAND.

SPECIFICATION forming part of Design No. 27,309, dated July 6, 1897.

Application filed May 21, 1897. Serial No. 637,604. Term of patent 7 years.

To all whom it may concern:

Be it known that I, JAMES F. CROOKER, a citizen of the United States, residing at Buffalo, in the county of Erie and State of New York, 5 have invented and produced a new and original Design for Bicycle-Stands, of which the following is a specification, reference being had to the accompanying drawing, forming a part thereof.

10 This design relates to the configuration of the stands employed for holding a bicycle in an upright position and for supporting the same while cleaning or examining it.

15 The accompanying drawing is a perspective view of a bicycle-stand embodying my design.

As shown in the drawing, the leading or material feature of my design consists of an inclined frame or standard composed of two parallel members or bars A A, rising from a 20 transverse base-bar B and having narrow lower portions b and wide upper portions b', forming a narrow space c between the wide

upper portions and a wide space c' between the narrow lower portions. The wide portions b' are tapered upwardly and rounded at 25 their upper ends and extend downward from the top of the bars A for about one-third of their length.

B is an inclined brace-bar extending downward from the junction of the wide and narrow portions of the parallel bars A. E represents inclined stay-bars extending forwardly and downwardly from the upper portion of the brace-bar to the lower portions of the parallel bars A. 30 35

What I claim is—

The design for a bicycle-stand, substantially as herein shown and described.

Witness my hand this 20th day of May, 1897.

JAMES F. CROOKER.
